(57) **CLAIM**

The ornamental design for a charging stand for electronic devices, as shown and described.

DESCRIPTION

FIG. 1 is a front perspective view of a charging stand for electronic devices showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;

FIG. 9 is a cross-sectional view of a charging stand for electronic devices taken in the direction of line 9-9 of FIG. 7; and,

FIG. 10 is the front perspective view thereof shown in an environment of use.

The broken lines in the drawing figures depict portions of the charging stand for electronic devices and environmental subject matter that form no part of the claimed design.

1 Claim, 10 Drawing Sheets
